ICE MACHINE

Dezell Ostrander, Coco Solo, C. Z.

Application April 7, 1943, Serial No. 482,172

18 Claims. (Cl. 83—62)

This invention relates to a machine for furnishing shaved ice or chipped ice as need therefor may occur, and the primary object of the invention is the provision of a durable and compact machine for the purpose specified which may be easily and quickly set up for use in a comparatively small space and will permit through a minimum expenditure of manual labor, ice shavings or ice chips to be obtained in amounts desired with the shaved ice and the ice chips kept separately and either dispensable from a common discharge.

Another object of the invention is the provision of a machine of the above stated character which will permit the shaved or chipped ice to be obtained from a block of ice of a standard size and in a sanitary manner substantially free of human contact.

A further object of this invention is the provision of a machine of the character stated which embodies a portable collection unit in which the shaved ice and ice chips are separately contained and which may be easily carried from place to place and includes means for dispensing either the shaved ice or the ice chips into different kinds of containers.

With these and other objects in view as will become more apparent as the description proceeds, the invention consists in certain novel features of construction, combination and arrangement of parts as will be hereinafter more fully described and claimed.

For a complete understanding of my invention, reference is to be had to the following description and accompanying drawings, in which

Figure 1 is a side elevation illustrating an ice machine constructed in accordance with my invention.

Figure 2 is a front elevation illustrating the device.

Figure 3 is a fragmentary longitudinal sectional view illustrating the cutting mechanism of the present invention, as well as the feed mechanism for advancing the ice to the cutting mechanism.

Figure 4 is a fragmentary top plan view illustrating the means of adjusting the cutting mechanism.

Figure 5 is a vertical sectional view illustrating the device.

Figure 6 is a transverse sectional view illustrating the knives of the cutting mechanism and the collection unit for the ice after being shaved or chipped.

Figure 7 is a transverse sectional view illus-

trating the mounting for the cutting mechanism and the drive means for said cutting mechanism.

Figure 8 is a top plan view of the collection unit.

Figure 9 is a fragmentary sectional view illustrating the mounting of the knives of the cutting mechanism.

Figure 10 is a fragmentary vertical sectional view illustrating a ratchet mechanism forming a part of the feed mechanism for the ice.

Figure 11 is a fragmentary sectional view of the ratchet mechanism.

Figure 12 is a fragmentary sectional view illustrating a friction brake for the lever of the ratchet mechanism.

Referring in detail to the drawings, the numeral 5 indicates an elongated cabinet, one end of which is fully open to permit the cabinet to be loaded with a block of ice. The open end of the cabinet forms the front of the latter and is equipped with a door 6 mounted on the cabinet by hinges 7 and held in closed position by latches 8 operable from the exterior of the door.

The cabinet 5 adjacent the front is provided with a depending portion 9 on the bottom so that when the cabinet is placed on a table, counter or the like, as shown in Figure 5, the depending portion 9 will be located normally in front of the support for the purpose of removably supporting on the cabinet a collecting unit 10. The bottom wall 11 of the cabinet terminates short of the open end of the cabinet so as to place the depending portion 9 in direct communication with the interior of the cabinet to receive ice shavings or ice chips from the cutting mechanism 12. The cutting mechanism 12 is mounted on the door 6 and is manually operated from the exterior of the cabinet for the purpose of shaving ice from the block of ice arranged within the cabinet or for chipping ice from the block of ice if desired so that the cut ice may gravitate into the depending portion 9 and then into the collecting unit 10. The collecting unit 10 is provided with front and rear compartments 13 and 14 separated from each other by a partition 15. The upper ends of the compartments communicate with an opening 16 provided in the bottom wall of the depending portion 9 and arranged for operation over the opening 16 is a gate 17 which may be positioned for directing cut ice into either of the compartments as shown in dotted lines in Figure 5. The gate will permit the shaved ice to be directed into one compartment and the chipped ice to be

directed into the other compartment of the collecting unit 10.

The gate 17 is carried by a shaft 18 journaled in the depending portion 9 and extends exteriorly thereof and is provided with an operating handle 19 whereby the position of the gate may be changed at the will of the operator.

The bottom wall of the depending portion 9 has angularly related flanges 20 to be engaged by flanges 21 of the collecting unit 10 so that the entire collecting unit may be applied and removed from the cabinet 5 at the will of the operator.

The compartments 13 and 14 are separable from the remaining construction of the collecting unit so that they as a unit may be removed from the collecting unit after the detachment of the latter from the cabinet and carried from place to place for the purpose of dispensing the cut ice from the compartments at a desired place.

A discharge spout 22 is integral with the compartments and common to both. The discharge spout 22 is controlled by swingable gates 23 carried by arms 24 one of which is integral with the shaft 25 and the other integral with a sleeve 26 journaled on the shaft 25. The shaft 25 is journaled in opposite walls of the compartments and the sleeve 26 extends along with the shaft 25 beyond one of the walls of the compartments and has secured thereto operating handles 27 oppositely disposed to each other, as shown in Figure 8, whereby the operator may swing either of the gates for opening either of the compartments to the discharge spout.

The movement of the arms 24 by the operating handles 27 will bring about agitation of the cut ice within the compartments to prevent the latter from massing and failing to flow freely to the discharge spout.

The bottom wall of the compartments on which the discharge spout 22 is formed is arcuately curved and the gates 23 are curved accordingly so as to match the curvature of the bottom wall. The bottom wall of the compartments has drain grooves 30 leading to the spout so that water may drain from the compartments to the discharge spout when the gates are in closed position to prevent excessive accumulation of water in the compartments along with the cut ice.

To prevent the water dripping from the spout 22 spilling onto a floor or the like, the lower portion of the collecting unit 10 is in the form of a skeleton frame and has removably mounted therein a tray or pan 31 located directly under the discharge spout 22 and spaced sufficiently far enough therefrom to permit various types of containers or receptacles to be placed under the discharge spout and within the pan or tray in order to obtain the ice from either of the compartments 13 or 14. A false bottom 32 is arranged in the pan or tray and is of foraminous material on which the different types of containers may rest and be kept from being positioned within the water caught in the pan or tray. The pan or tray is easily removable from the collecting unit 10 so that it may be emptied when need may occur.

A feed mechanism shaft 33 is journaled in the depending portion 9 of the cabinet and is arranged transversely of the cabinet under the bottom wall 11 thereof which protrudes partly over the depending portion and has secured thereto a plurality of spiked wheels 33' that extend through slots provided in the bottom wall 11 of the cabinet to bite into the block of ice so as to slide the block of ice toward the cutting mechanism

12 as the shaft 33 is rotated in one direction. It is preferable that the bottom wall 11 of the cabinet be provided with ribs 34 to support the block of ice from full contact with the bottom wall and thereby permit water melted from the ice to readily flow away from the block of ice and into the depending portion 9 resulting in less melting of the block of ice.

The shaft 33 extends at one end exterior of the depending portion 9 and has secured thereon a ratchet gear 34'. Also journaled on said end of the shaft is a hollow hub 35 of a hand lever 36. The hollow hub encloses the ratchet gear and has pivotally mounted therein a dog 37 engageable with the teeth of the ratchet gear under the influence of a spring 38. One end of the dog 37 is engaged by a cam 39 carried by a pin 40 journaled in the hub and extends exteriorly thereof and is provided with a finger piece 41 whereby the operator may disengage the dog from the ratchet gear 34' whenever it is desired for the hand lever 36 to move free of the feed shaft 33.

A lip 41' is formed on the hub 35 and has connected thereto a coil spring 42 which is suitably secured to the wall of the cabinet. The purpose of the spring 42 when tensioned is to swing the hand lever in one direction and when the dog 37 is in engagement with the ratchet gear to bring about rotation of the shaft 33 and thereby feed the block of ice to the cutting mechanism. The purpose of the hand lever 36 is to tension the spring 42 and to govern the movement of the hand lever 36 by the action of the spring 42, a friction brake 43 is adjustably secured to the free end of the hand lever and drags against one wall of the cabinet 5. The friction brake 43 is in the form of a disc 44 which contacts the wall of the cabinet, a shank 45 threaded in the hand lever and provided with a finger piece 46 whereby the pressure of the disc 44 against the wall of the cabinet may be varied by threading the shank 45 in opposite directions in the hand lever. The friction brake 43 governs the action of the feed mechanism in feeding the ice to the cutting mechanism. This, to some extent, will bring about a variance in the cutting action of the cutting mechanism on the block of ice so that larger or smaller chips may be obtained or a greater or less amount of ice shavings.

The entire cutting mechanism 12 and its operating means is mounted on the inner face of the door 6 so that when the door is in an open position the cutting mechanism is disposed entirely outwardly of the cabinet. This will facilitate the placing of a block of ice in the cabinet.

Secured to and spaced from the inner face of the door 6 is a wall 47. The space provided between the door and the wall 47 accommodates a drive gear 48 secured on a shaft 49 journaled in the wall 47 and the door and extends beyond the outer face of the door to which is secured a crank handle 50. Journaled in the space between the door and the wall 47 and above and below and in mesh with the gear 48 are gears 51, the shafts 52 thereof being equipped with cranks 53 provided with rollers 54 operating within a vertically arranged channel member 55 forming a part of the cutting mechanism 12 so that said cutting mechanism will be made to travel transversely of the cabinet at the front end of the block of ice arranged in said cabinet and in a back and forth direction. The gears 51 are rotated in the same direction by the drive gear 48 when the crank handle 50 is manually ro-

tated from a place exteriorly of the cabinet by the operator.

Upper and lower transversely arranged channel tracks 56 are secured to the wall 41 and are engaged by rollers 57 journaled on stub shafts 58 secured to angle iron brackets 59 secured to the upper and lower portions of the cutting mechanism 12. This construction will permit the cutting mechanism to reciprocate transversely of the cabinet at one end of the block of ice with a minimum amount of friction by the drive mechanism.

The cutting mechanism 12 includes a substantially rectangular shaped frame 60 secured to the angle iron brackets 59 and when the door is in a closed position is supported at one end of the block of ice. The frame 60 is provided with a plurality of spaced longitudinally extending partitions 61, the longitudinally exposed edges thereof being serrated to form teeth 62 for scoring the end of the block of ice during the reciprocation of the frame by the drive mechanism against the end of the block of ice.

Journalized in the frame and arranged vertically is a plurality of knife shafts 64 which extend through notches provided in the partitions and have journaled thereon hubs 65 of knife blades 66. The knife blades mounted on each shaft are all integral with a single hub which is journaled on the shaft. The free ends of the knife blades are sharpened and beveled to form cutting edges. The hubs are secured to the shafts 64 and connected to said shafts are springs 67 that bear against pins 68 carried by the frame 60. The action of the springs 67 is to urge the free ends of the blades outwardly of the frame for contact with the end of the block of ice between the partitions so that the knife blades will act upon the ice between the scored lines formed by the teeth 62 of the partitions of the frame. The knife blades extend at an angle outwardly of the frame between the partitions, so that their free cutting edges will act to cut the ice on the movement of the frame in one direction relative to the end of the block of ice and to move freely over the block of ice when the frame moves in a reverse direction.

Therefore, it will be seen by the rotation of the crank handle 50, the knife blades will be made to either shave ice particles off of the end of the block of ice or by adjusting the action of the knife blades through a suitable adjusting means, which will be hereinafter more fully described, may be made to cut the ice into larger particles so as to produce a sort of crushed ice. By having the gate 17, the operator can direct the pulverized ice into one of the compartments of the collecting unit while the crushed ice may be directed into the other compartment.

The shafts 64 of the knife blades 66 are provided with pins 69 engaged by a plate 70. The plate 70 is slideable on top of the frame 60 and against the pins 69. The plate 70 is arranged at the upper end of the frame 60 and has attached thereto rods 71 extending through openings provided in angle iron plate 59 and secured to plate 72. During the reciprocation of the knife frame 60 the plate 70 moves therewith, also rods 71, and the plate 72. However, the plate 72 may be made to slide toward and from the frame 60 with plate 70 having a relative movement on top of frame 60 and the rods 71 being fastened thereto will cause the pressure plate 70 to act on the pins 69 for either extending or retracting the 76

knife blades with respect to the frame 60 to govern the depth of cut the knife blades will make in a block of ice to either produce large particles of ice or the fine particles.

5 The operating plate 72 is provided with a slot 73 in which a squared portion 74 of an operating rod 75 engages. Collars 76 are secured on the operating rod 75 and spaced to engage opposite faces of the operating plate 72, still permitting the operating plate to have sliding movement with the cutting mechanism relative to the operating rod 75 which is journaled in the wall 41 and the front door, the outer end of which is provided with a finger piece 76' whereby the operating rod 75 may be operated. The finger piece 76' is threaded onto the operating rod 75 and bears against the outer face of the door 6. By rotating the finger piece 76' in opposite directions on the operating rod 75, the latter will be allowed to slide in opposite directions bringing about a sliding movement of the operating plate 72 in opposite directions which in turn causes the plate 70 which is secured to plate 72 by rods 71 to act on the pins 69 of the knife shafts in opposite directions to extend or retract the knife blades relative to the end of the block of ice, thereby regulating the depth of cuts made by the knife blades between the score lines on the block of ice to produce either the pulverized ice shavings or chips of ice. The deeper the knife blades cut into the block of ice during their reciprocation relative thereto the larger the particles of ice will be cut from the block of ice. The less the knife blades cut into the block of ice the smaller will be the particles of ice cut from the block of ice.

20 A signal member 80 is pivotally mounted on the cabinet 5 and includes an angularly disposed arm 81 which carries at its free end a roller 83 that rides upon the top face of the block of ice, maintaining the signal element in a lowered position. However, when the roller 83 engages with the inner end of the block of ice it follows the latter and allows the signal member to move upwardly into signaling position indicating that the amount of ice in the cabinet is nearing exhaustion.

25 From the foregoing description taken in connection with the accompanying drawings, it will be seen that a very practical machine is provided for cutting ice in block form into either extremely small or pulverized particles or into chips and that means is provided for the collection of the differently cut ice into separate compartments of 30 a collecting unit, which compartments are of integral construction and can be readily separated from the machine and carried from one place to another.

35 Further, it will be seen that the compartments 60 of the collecting unit are equipped with means for dispensing the different cut sizes of ice through a common discharge and at the same time agitating the cut ice within the compartments. It may not always be desirable that the compartments be removed from the collecting unit and carried from place to place and when not removed they may remain in the collecting unit and different types of containers may be arranged on the tray 31 under the discharge spout to receive the cut ice. All of this can be easily and quickly carried out with a minimum amount of manual effort without the operator coming in direct contact with the ice. The only human contact with the ice is necessary when placing the block of ice within the cabinet which can be easily accom-

plished due to the fact that the door and the cutting mechanism carried thereby can be swung to a fully open position, leaving one end of the cabinet fully open so that the block of ice may be freely slid into the cabinet. In order that the feeding mechanism or the spiked wheels 31 thereof will not interfere with the placing of the block of ice in the cabinet, the dog 37 may be freed of the ratchet gear 34 allowing the shaft 33 to rotate freely with the block of ice during its sliding movement into the cabinet.

While I have shown and described the preferred embodiment of my invention, it will be understood that minor changes in construction, combination and arrangement of parts may be made without departing from the spirit and scope of the invention as claimed.

Having thus described my invention, what I claim is:

1. In an ice machine, a cabinet open at one end to receive a block of ice, a hinged door for opening and closing the cabinet, a cutting mechanism carried by the door and operable from the exterior of the cabinet for cutting the ice into fine and coarse particles, a collection unit removably mounted on the cabinet and in communication with the interior thereof and including separate compartments separable from said unit to receive fine and coarse particles of ice, and means for directing the fine cut ice into one compartment and the coarse cut ice into the other compartment.

2. In an ice machine, a cabinet open at one end to receive a block of ice, a hinged door for opening and closing the cabinet, a cutting mechanism carried by the door and operable from the exterior of the cabinet for cutting the ice into fine and coarse particles, a collection unit removably mounted on the cabinet and in communication with the interior thereof and including separate compartments separable from said unit to receive fine and coarse particles of ice, means for directing the fine cut ice into one compartment and the coarse cut ice into the other compartment, a discharge spout common to both compartments, gates for controlling the spout of the compartments.

3. In an ice machine, a cabinet open at one end to receive a block of ice, a hinged door for opening and closing the cabinet, a cutting mechanism carried by the door and operable from the exterior of the cabinet for cutting the ice into fine and coarse particles, a collection unit removably mounted on the cabinet and in communication with the interior thereof and including separate compartments separable from said unit to receive fine and coarse particles of ice, means for directing the fine cut ice into one compartment and the coarse cut ice into the other compartment, a discharge spout common to both compartments, gates for opening and closing the spout to the compartments, and operating means for each gate.

4. In an ice machine, a cabinet open at one end to receive a block of ice, a hinged door for opening and closing the cabinet, a cutting mechanism carried by the door and operable from the exterior of the cabinet for cutting the ice into fine and coarse particles, a collection unit removably mounted on the cabinet and in communication with the interior thereof and including separate compartments separable from said unit to receive fine and coarse particles of ice, means for directing the fine cut ice into one compartment and the coarse cut ice into the other compartment,

partment, a discharge spout common to both compartments, gates for opening and closing the spout to the compartments, operating means for each gate, and a removable tray arranged under and spaced from the spout and carried by the collection unit and including a false foraminous bottom.

5. In an ice machine, a cabinet open at one end to receive a block of ice, a door hinged to said cabinet for opening and closing the cabinet, a cutting mechanism mounted for reciprocation on the door and adapted to act on the ice for cutting the latter into fine and coarse particles, means for adjusting the cutting mechanism to vary its cutting action on the block of ice to produce the fine and coarse particles, and an operating means for the cutting mechanism and arranged to permit actuation thereof exteriorly of the door.

6. In an ice machine, a cabinet open at one end to receive a block of ice, a door hinged to said cabinet for opening and closing the cabinet, a cutting mechanism mounted for reciprocation on the door and adapted to act on the ice for cutting the latter into fine and coarse particles, means for adjusting the cutting mechanism to vary its cutting action on the block of ice to produce the fine and coarse particles, an operating means for the cutting mechanism and arranged to permit actuation thereof exteriorly of the door, and a feed mechanism for advancing the block of ice to the cutting mechanism.

7. In an ice machine, a cabinet open at one end to receive a block of ice, a door hinged to said cabinet for opening and closing the cabinet, a cutting mechanism mounted for reciprocation on the door and adapted to act on the ice for cutting the latter into fine and coarse particles, means for adjusting the cutting mechanism to vary its cutting action on the block of ice to produce the fine and coarse particles, an operating means for the cutting mechanism and arranged to permit actuation thereof exteriorly of the door, a shaft journaled on the cabinet, spiked wheels secured to said shaft and engaging the block of ice, a hand lever journaled on said shaft, a ratchet mechanism between said hand lever and the shaft and capable of being actuated to release the hand lever from the shaft, and a spring connected to the hand lever for moving the latter in one direction to rotate the shaft to bring about the advancement of the ice relative to the cutting mechanism.

8. In an ice machine, a cabinet open at one end to receive a block of ice, a door hinged to said cabinet for opening and closing the cabinet, a cutting mechanism mounted for reciprocation on the door and adapted to act on the ice for cutting the latter into fine and coarse particles, means for adjusting the cutting mechanism to vary its cutting action on the block of ice to produce the fine and coarse particles, an operating means for the cutting mechanism and arranged to permit actuation thereof exteriorly of the door, a shaft journaled on the cabinet, spiked wheels secured to said shaft and engaging the block of ice, a hand lever journaled on said shaft, a ratchet mechanism between said hand lever and the shaft and capable of being actuated to release the hand lever from the shaft, a spring connected to the hand lever for moving the latter in one direction to rotate the shaft to bring about the advancement of the ice relative to the cutting mechanism, and a friction brake carried by the hand lever and engageable with the cabinet for varying the movement of the hand lever by the spring.

9. In an ice machine, a cabinet open at one end to receive a block of ice, a door hinged to said cabinet for opening and closing the cabinet, a cutting mechanism mounted for reciprocation on the door and adapted to act on the ice for cutting the latter into fine and coarse particles, means for adjusting the cutting mechanism to vary its cutting action on the block of ice to produce the fine and coarse particles, an operating means for the cutting mechanism and arranged to permit actuation thereof exteriorly of the door, a shaft journaled on the cabinet, spiked wheels secured to said shaft and engaging the block of ice, a hand lever journaled on said shaft, a ratchet mechanism between said hand lever and the shaft and capable of being actuated to release the hand lever from the shaft, a spring connected to the hand lever for moving the latter in one direction to rotate the shaft to bring about the advancement of the ice relative to the cutting mechanism, and a friction brake carried by the hand lever and engageable with the cabinet for varying the movement of the hand lever by the spring, a signal element pivotally mounted on the cabinet and engaging the block of ice.

10. In an ice machine, a cabinet open at one end to receive a block of ice, a hinged door for opening and closing the cabinet, a track carried by the door and adapted to assume a position within the cabinet when the door is in a closed position, a knife frame slidably supported by the track at one end of the block of ice including a series of knives, and an operating means carried by the door for the reciprocation of the knife blades.

11. In an ice machine, a cabinet open at one end to receive a block of ice, a hinged door for opening and closing the cabinet, a track carried by the door and adapted to assume a position within the cabinet when the door is in a closed position, a knife frame slidably supported by the track at one end of the block of ice including a series of knives, a channel member secured to the frame, cranks engaging with the channeled member and journaled on the door, a master gear journaled on the door, gears secured to the cranks and meshing with the master gear, and a crank handle secured to the master gear and arranged on the outer face of the door.

12. In an ice machine, a cabinet to receive a block of ice, a door for opening and closing the cabinet, a knife frame slidably mounted on the door and adapted to assume a position adjacent one end of the block of ice when the door is in closed position, a plurality of knife shafts journaled in said frame, knife blades journaled on said shafts for action on the block of ice, tension means acting on the knife blades to urge them into cutting position with respect to the block of ice, means for regulating the cutting action of the knife blades on the block of ice, and an operating means for reciprocating the frame relative to the block of ice and operable from the outer face of the door.

13. In an ice machine, a cabinet to receive a block of ice, a door for opening and closing the cabinet, a knife frame slidably mounted on the door, means for reciprocating the knife frame, a plurality of knife blades pivotally mounted in the frame for action on the block of ice, tension means acting on said blades to urge them into cutting position, partitions carried by said frame and provided with serrated edges arranged between the knife blades to score the ice block during the reciprocation of the frame, and means

operable from the exterior of the door to reciprocate the frame.

14. In an ice machine, a cabinet to receive a block of ice, a door for opening and closing the cabinet, a knife frame slidably mounted on the door, means for reciprocating the knife frame, a plurality of knife blades pivotally mounted in the frame for action on the block of ice, tension means acting on said blades to urge them into cutting position, partitions carried by said frame and provided with serrated edges arranged between the knife blades to score the ice block during the reciprocation of the frame, means operable from the exterior of the door to reciprocate the frame, and means operable from the exterior of the door to adjust the cutting action of the blades on the ice.

15. In an ice machine, a cabinet to receive a block of ice, a door for opening and closing the cabinet, a knife frame slidably mounted on the door, means for reciprocating the knife frame, a plurality of knife blades pivotally mounted in the frame for action on the block of ice, tension means acting on said blades to urge them into cutting position, partitions carried by said frame and provided with serrated edges arranged between the knife blades to score the ice block during the reciprocation of the frame, means operable from the exterior of the door to reciprocate the frame, and means operable from the exterior of the door to adjust the cutting action of the blades on the ice.

16. In an ice machine, a cabinet to receive a block of ice, a door for opening and closing the cabinet, a knife frame slidably mounted on the door, means for reciprocating the knife frame, a plurality of knife blades pivotally mounted in the frame for action on the block of ice, tension means acting on said blades to urge them into cutting position, partitions carried by said frame and provided with serrated edges arranged between the knife blades to score the ice block during the reciprocation of the frame, means operable from the exterior of the door to reciprocate the frame, and means operable from the exterior of the door to adjust the cutting action of the blades on the ice, a feeding mechanism carried by the cabinet to advance the block of ice to the cutting knives as the latter cut particles of ice from the block, said cabinet having a depending portion to receive the cut ice and provided with an opening, and a collection unit removable from the depending portion and including compartments to receive fine cut ice cut by the knife blades, and a gate pivotally mounted in the depending portion for directing the finely cut ice into one compartment and the coarse cut ice into the other compartment.

17. In an ice machine, a cabinet to receive a block of ice, a door for opening and closing the cabinet, a knife frame slidably mounted on the door, means for reciprocating the knife frame, a plurality of knife blades pivotally mounted in the frame for action on the block of ice, tension means acting on said blades to urge them into cutting position, partitions carried by said frame and provided with serrated edges arranged between the knife blades to score the ice block during the reciprocation of the frame, means operable from the exterior of the door to reciprocate the frame, and means operable from the exterior of the door to adjust the cutting action of the blades

on the ice, a feeding mechanism carried by the cabinet to advance the block of ice to the cutting knives as the latter cut particles of ice from the block, said cabinet having a depending portion to receive the cut ice and provided with an opening, a collection unit removable from the depending portion and including compartments to receive fine cut ice cut by the knife blades, and a gate pivotally mounted in the depending portion for directing the fine cut ice into one compartment and the coarse cut ice into the other compartment, and a dispensing means common to both compartments and including control gates one for each compartment to control the escape of ice from the compartments to the discharge spout, and means whereby the latter-named gates may be independently operated.

18. In an ice machine, a cabinet to receive a block of ice, a door for opening and closing the

cabinet, a cutting frame slidably mounted on said door for reciprocation with relation to one end of the block of ice and including a plurality of spaced partitions having serrated edges for 5 scoring the block of ice, knife shafts journaled in the frame, knife blades secured to said shafts and operable between the partitions for shaving the ice between the scored lines, tension means acting on the knife blades to urge them into cutting position, means carried by the door and operable from the exterior thereof for reciprocating the frame, pins carried by said shafts, a plate engaging said pins, rods secured to said plate, an operating plate secured to said rods and having a slot, an operating rod extending into the slot and having a squared portion to fit said slot 10 to bring about variance in the cutting action of the blades on the ice and operable from the exterior of the door.

DEZELL OSTRANDER.
